UNITED STATES PATENT OFFICE.

WILLIAM C. WOOD, OF CENTRALIA, ILLINOIS.

BANK PROTECTIVE APPARATUS.

Application filed December 17, 1920. Serial No. 431,376.

To all whom it may concern:

Be it known that I, WILLIAM C. Wood, a citizen of the United States of America, residing at Centralia, in the county of Marion and State of Illinois, have invented new and useful Improvements in Bank Protective Apparatus, of which the following is a specification.

The object of the invention is to provide means for effectively protecting banks and similar financial institutions which are normally accessible to the public during business hours and hence are made the object of attack for the purpose of robbery by men who hold the tellers located at the paying windows under restraint by means of fire arms or by actually attacking such officials before means of protecting the funds of the institution can be utilized, and it is therefore the purpose specially of the present invention to provide protective, bullet proof curtains or shields which may be moved into position to protect the tellers and the funds and portable securities in their position, or into position between the tellers and anyone located outside of the screen or grating of the bank or like institution, and also to provide means whereby egress from the bank or like building through the doorway giving access thereto under normal conditions may be closed or barred to trap and prevent the escape of the robber or like assailant, together with means whereby the proper custodians may be summoned for the purpose of effecting a capture; and with these objects in view the invention consists in a construction and combination of parts of which a preferred embodiment is shown in the accompanying drawing, wherein:

Figure 1 is a view of the apparatus applied in the operative position to a diagrammatically indicated representation of a portion of a bank or like establishment.

Figure 2 is a perspective view of the apparatus showing the connections between the elements thereof and the means whereby the positions thereof are maintained under normal conditions, subject to momentary release in the event of a threatened attack.

The apparatus contemplates essentially a movable guard or curtain 10 preferably of bullet proof construction and either weighted or of sufficient weight of itself to effect its movement when released into a protective position with relation to a teller's window, indicated at 11, in a screen or grating

12 such as usually interposed in a bank or like institution between the inner offices or stations of the bank officials as indicated at 13, and the lobby or corridor accessible to the public which is indicated at 14, and which may be entered during business hours through an opening 15 which may as in the ordinary practice be closed at other times by a suitable door 16, together with means for normally holding the protective curtain or shield 10 in an inoperative position subject to release at any time for closing the teller's window and affording a guard by which the official stationed at such window may be protected.

In the construction illustrated the curtain or shield 10 is connected with a counterweighting plate 17 by means of cables 18 extending over suitable direction pulleys 19, the counterweighting element being of less weight than the curtain or shield so as to permit of the prompt but moderated dropping of the latter when released, and for supporting said curtain or shield in its inoperative position there is employed a rock shaft 19' provided with arms 20 held in the path of the lower edge of the curtain or shield by means of pawls 21 engaging ratchets 22.

The release of the rock shaft by the disengagement of the pawls may be effected in a variety of ways but as shown the mechanism embodies drums 23 upon which is reeled cables 24 extending over direction pulleys 25 and connected with the pawls, said drums being mounted on a common shaft which is normally held against rotation by means of a ratchet 26 engaged by a pawl 27 to which is connected a treadle 28 within convenient reach of a teller standing at the paying window. A drum actuating weight 29 may be employed as indicated to insure the prompt turning of the drums when released by the disengagement of the pawls 27 to effect the momentary disengagement of the pawls 21 from the ratchets 22, so that the descent of the protective curtain or shield may be effected with sufficient promptness to insure the safety of the teller. Also a further connection may be made between the drum 30' and the counterweighting plate 17 by means of a cable 30, the drum 30' being carried by the same shaft as the drums 23.

In connection with the foregoing mechanism there is also preferably employed a barrier consisting of a weighted plate 31 nor-

mally held in an elevated position adjacent to the entrance opening 15 to the public lobby or corridor and connected by cables 32 with a counterweighting plate 33, said barrier being normally held in an elevated or inoperative position by arms 34 on a rock shaft 35 held in place by ratchets 36 engaged by pawls 37 which in turn are connected for tripping operation with the drums 23 by means of cables 38, so that when the drums are released to permit the movement of the protective curtain or shield into operative position, the barrier is simultaneously released to drop and close the entrance door opening so as to cut off the escape of anyone who has attempted an attack upon the officials of the institution. Obviously any suitable means may be arranged within convenient reach of the teller for notifying and summoning the bank watchman or other officials to assist in capturing or restraining the assailant.

It will also be understood that whereas the foot treadle within reach of the official 25 stationed at the paying window serves as a convenient means of releasing the protective devices, this feature is subject to modification to suit the location of the window or the duties of the official, the several positions 30 which he may occupy in the discharge of his duties when subject to attack and the like, and owing to the plane of operation of the protective curtain or shield it will be seen that it not only serves to interpose a bullet 35 proof obstacle between the assailant and his intended victim, but cuts off access from the outside through the window so as to protect the funds and portable securities which may of necessity be stored adjacent thereto for 40 convenience in the transaction of the business of the institution.

Having described the invention what is claimed as new and useful is:

1. A protective apparatus for banks and similar institutions consisting of a bullet 45 proof curtain or shield located adjacent to

the plane of a screen or partition in which is arranged a teller's window, and movable into position to bar or obstruct said window, means for normally maintaining said curtain or shield in an inoperative position, and means for tripping or releasing the curtain retaining means, the said retaining means consisting of a rock shaft having supporting arms for bearing the weight of the curtain or shield and ratchet mechanism for maintaining the rock shaft in its normal position, and said trip mechanism consisting of yieldingly impelled drums flexibly connected with the pawls of said ratchet mechanism, and a treadle actuated pawl for maintaining the drums in their normal positions.

2. A protective apparatus for banks and similar institutions consisting of a bullet proof curtain or shield located adjacent to the plane of a screen or partition in which is arranged a teller's window, the said curtain being movable into obstructive relation with said window, a counterweight for said curtain; cables connecting said counterweight with said curtain, guide sheaves over which said cables are trained, a rock shaft disposed in transverse spanning relation with said window opening and provided with retaining arms engaging under the lower edge of said curtain, ratchets engaging said rock shaft, pivotally mounted pawls engaging said ratchet, a second shaft disposed below the plane of said window and provided with drums adjacent its opposite extremities, cables reeled on said drums and trained over guide pulleys and terminally connected with said pawls, a foot controlled lock for said second shaft, an intermediately disposed drum carried on said second shaft, and a cable reeled on the last said drum and carried over direction pulleys and terminally connected with said counterweight as herein shown and specified.

In testimony whereof he affixes his signature.

WILLIAM C. WOOD.
